CLAIM

I claim the ornamental design for the collapsible colander, as shown and described.

DESCRIPTION

FIG. 1 is a top perspective view of a collapsible colander showing my new design;

FIG. 2 is a front view of the collapsible colander;

FIG. 3 is a top view of the collapsible colander;

FIG. 4 is a back view of the collapsible colander;

FIG. 5 is a left side view of the collapsible colander, the right side view being a mirror image; and,

FIG. 6 is a bottom view of the collapsible colander.
